UNITED STATES PATENT OFFICE.

WILLIAM B. SMITH, OF PLAINFIELD, NEW JERSEY, ASSIGNOR OF ONE-HALF
TO HAROLD P. BROWN, OF MONTCLAIR, NEW JERSEY.

ARTIFICIAL FUEL.

SPECIFICATION forming part of Letters Patent No. 724,214, dated March 31, 1903.

Application filed January 14, 1903. Serial No. 138,962. (No specimens.)

To all whom it may concern:

Be it known that I, WILLIAM B. SMITH, a citizen of the United States, and a resident of Plainfield, in the county of Union and State 5 of New Jersey, have invented a new and useful Artificial Fuel, of which the following is a specification.

My invention relates to an artificial fuel, with the object in view of utilizing materials 10 which are at the present time considered nuisances and waste products.

With this end in view my invention consists in an artificial fuel composed of the residuum from the manufacture of acetylene 15 gas and carbonaceous material—such, for example, as ashes and cinders from the burning of wood and coal.

The fuel may be practically manufactured as follows: The ashes and cinders may be 20 spread on a floor and a sufficient amount of the slush or watery residuum from an acetylene-gas machine may be poured onto the ashes and cinders in quantities sufficient to 25 make the mixture the consistency of ordinary mortar for laying up brick and stone. The ashes and cinders and residuum from the gas- 30 machine may then be thoroughly mixed, using for the purpose a hoe or shovel, so that as far as may be every particle of cinder and ash 35 shall be covered with the residuum. This mixture is allowed to remain on the floor for one or two hours, but not long enough for it to become dry and hard, as I find it to be 40 much better to use it in the furnace while it is still in a wet plastic condition. The mixture may then be spread onto a fire already started in a furnace and will efficiently serve as a fuel, maintaining the fire in the furnace without the use of any coal or any other fuel

45 formed one, is as follows: The residuum (containing hydrate of lime, hydrocarbon in solution, hydrochloric acid, and carbonic acid) when distributed over the ash and cinder has a great affinity for the poisonous gases of the

atmosphere, which it quickly absorbs, and it 50 is for the purpose of absorbing these that I allow the mixture to remain for one or two hours in order that it may take from the atmosphere the carbonic acid and such nitrogenous gases as may be floating in the vicinity. 55 When this mixture is finally placed on hot burning coals, it gathers an atom of carbon from the ash and cinder, thereby breaking down the carbonic acid and forming carbon-monoxide gas, which immediately ignites. 60 This gas continues to form as long as there is any carbonic acid in the mixture or surrounding air. The heat is very intense, and portions of the mixture can be added from time to time and the fire continued indefinitely. 65

One of the economic features of this fuel is that the cinder which results from the burning of this artificial fuel may be itself broken up again and mixed with a fresh quantity of 70 the residuum from the acetylene-gas machine, to be again used in the furnace. When the ash and cinder have been used in this manner several times over, the mixture may be materially improved by using sulfate of iron 75 with the ash and cinder—for example, a pound of the sulfate of iron to one hundred pounds of the mixture, although this proportion is not of material importance and may be varied as convenience or experience may prove desirable. 80

What I claim is—

1. An artificial fuel consisting of the residuum from the manufacture of acetylene gas and ash and cinder. 85

2. An artificial fuel consisting of a mixture of the residuum from the manufacture of acetylene gas, ash and cinder and sulfate of iron.

In testimony that I claim the foregoing as 90 my invention I have signed my name, in presence of two witnesses, this 13th day of January, 1903.

WILLIAM B. SMITH.
